CONVERSION OF HYDROCARBONS

Hillis O. Folkins, Skokie, and Carlisle M. Thacker,
Highland Park, Ill., assignors to The Pure Oil
Company, Chicago, Ill., a corporation of Ohio

No Drawing. Application December 26, 1942,
Serial No. 470,304

1 Claim. (Cl. 260—633)

1

This invention relates to a method for converting higher boiling hydrocarbons into lower boiling hydrocarbons and to a method of producing unsaturated hydrocarbons from saturated hydrocarbons.

An object of the invention is to convert higher boiling hydrocarbons into lower boiling hydrocarbons.

Another object of the invention is to provide a method of accelerating the rate of conversion of higher boiling into lower boiling hydrocarbons.

A still further object of the invention is to provide a method for preparing unsaturated hydrocarbons from saturated hydrocarbons.

A further object of the invention is to accelerate the cracking of saturated to unsaturated hydrocarbons.

Still another object of the invention is to provide a method of accelerating cracking of hydrocarbons under known thermal conditions and in present types of cracking apparatus.

Other objects and advantages inherent in the invention will become apparent from the following description.

We have discovered that thermal conversion of hydrocarbons into lower boiling hydrocarbons and/or into unsaturated hydrocarbons can be accelerated by introducing into the hydrocarbons undergoing conversion a small amount of sulfur, hydrogen sulfide, and/or organic sulfur compounds, preferably mercaptans, sulfides, disulfides and other alkyl sulfur compounds.

The particular compound or compounds selected as sensitizers should preferably be in the same phase (liquid or vapor) as the charging stock at the temperature of reaction. As examples of sulfur compounds, which we have found useful, may be mentioned methyl, ethyl, n-propyl, iso-propyl, n-butyl, iso-butyl, tertiary butyl, n-amyl and iso-amyl mercaptans; methyl, ethyl, n-propyl, allyl, methyl ethyl, methyl n-butyl and ethyl n-butyl sulfides; and methyl and ethyl disulfides.

2

For the purpose of this invention organic compounds are those having both carbon and hydrogen in the molecule.

We have found that when sulfur, hydrogen sulfide and/or organic sulfur compounds are mixed with hydrocarbons undergoing conversion in an amount of 3 molal per cent or less, a marked acceleration in the rate of cracking occurs at temperatures above 375° C. Sensitizers, in accordance with our invention, are effective at sub-atmospheric, atmospheric and super-atmospheric pressure.

In order to demonstrate the effectiveness of various compounds falling within the scope of our invention, a number of tests were made in both a Pyrex reaction vessel and in a stainless steel reaction vessel. The results of these tests are set forth in Tables I, II and III. In the great majority of tests normal butane was used as the charging material. Some of the tests were conducted with pentane as the charging stock. The tests were carried out by heating the reaction vessel to reaction temperature (either 500° or 525° C.), evacuating it, injecting into the evacuated vessel sufficient butane (or pentane), containing the desired amount of sensitizer, to produce the desired initial pressure (usually about 1 atmosphere), allowing the reaction to proceed until a pressure increase of 25% over the initial pressure was obtained, and then rapidly removing reaction gases for analysis. The time required for an increase in pressure of 5, 12.5 and 25 per cent was recorded. A number of blank runs in which no sensitizer was used were made in order to obtain a comparison with the sensitized runs. In the last column of the tables the sensitization factor is the quotient of the time required for 25 per cent pressure increase for a non-sensitized run divided by the time required for the same pressure increase in a sensitized run. In Table I the tests were all carried out at a temperature of 525° C.

Although mercaptans, sulfides, disulfides and hydrogen sulfide all generally accelerated the rate of cracking of normal butane, as shown in Table I,

the sulfides appear to have the greatest sensitizing effect.

The runs tabulated in Table II were all performed at 500° C. and had an initial pressure of approximately 400 mm. with the exception of those runs marked with an asterisk.

Table III is a tabulation of the gas analyses by volume per cent of the gases produced in the runs tabulated in Tables I and II. The gas analyses demonstrate that the composition of the gas produced in the cracking operation is fairly uniform, regardless of whether or not a sensitizer is used. The analyses also show that a considerable portion of the butane and pentane charged in the various runs was converted to unsaturated hydrocarbons and that very little hydrogen was produced in these runs, thereby demonstrating that the cracking took place between the carbon bonds rather than between carbon and hydrogen.

In order to demonstrate the efficacy of sensitizers in accordance with our invention, when used in a continuous type process, a series of runs were made using Stoddard's solvent as a charging stock in a flow apparatus. The Stoddard's solvent had an A. P. I. gravity of 48.1, an initial boiling point of 305, and an end point of 390. The total sulfur content was .03 and the solvent contained no mercaptan sulfur. The results of these runs are recorded in Table IV. In making these runs the Stoddard's solvent was preheated in a stainless steel tube of $\frac{1}{4}$ " diameter and was then charged to a stainless steel reactor having a diameter of 3" and a length of 9 $\frac{1}{4}$ ". The temperatures of the preheater and reactor were maintained by an external electric heating element.

Runs 415 and 420 are blank runs. Runs 416 and 423 were carried out with hydrogen sulfide as the sensitizer. Run 425 was carried out with methyl sulfide as the sensitizer. The sensitizer was added to the Stoddard's solvent before it was charged to the preheater coil.

From the results tabulated in Table IV it will be seen that sensitizer produced a liquid product which had a lower initial boiling point and a higher octane number than the product prepared without a sensitizer, thereby definitely showing that higher cracking took place with the sensitizer in the same period of time than without the sensitizer. A further indication of the greater extent of cracking in the sensitized runs is the bromine number showing a larger proportion of unsaturates in the distillate made in the sensitized runs than in the non-sensitized runs.

The analyses of the liquid product for sulfur compound indicate that by a simple aqueous caustic soda wash of the distillate the amount of sulfur compounds in the distillate can be reduced to a point where they are unobjectionable.

The invention is applicable to cracking of both low boiling and high boiling hydrocarbons within the range of 375° C. to approximately 700° C. The sensitizers are effective in very small amounts and when cracking gasoline or higher boiling hydrocarbons, should be used in amounts below 1 per cent by weight of the charge since larger amounts not only cause corrosion difficulties but deleteriously affect the quality of the product. Good results are obtained by using from 0.25 to 1 molal per cent of the sensitizer.

The sensitizer may be added to the hydrocarbons under going cracking prior to charging the latter to the heating zone or may be injected directly into the reaction zone either alone or in admixture with a small amount of solvent.

The invention is useful in connection with conventional thermal cracking operations to accelerate the rate of cracking or may be used in connection with catalytic cracking operations of the stationary or moving bed catalyst type, or in conjunction with vapor suspended solid catalyst type of operation, in which solid, comminuted catalytic clays or synthetic alumina-silica or other solid catalysts are used.

What is claimed is:

10 The method of cracking butane to lower boiling unsaturated hydrocarbons which comprises subjecting it to temperatures above 375° C. in the presence of a small amount of ethyl sulfide.

15 H. O. FOLKINS.
